Application August 6, 1948, Serial No. 147,969

Term of patent 14 years

(Cl. D21--6)

To all whom it may concern:

Be it known that I, Louis Arabit, a citizen of the United States, residing in Houston, Harris County, Texas, have invented a new, original, and ornamental Design for Shingle Awnings or the like, of which the following is a specification, reference being had to the accompanying drawing, forming a part thereof.

Figure 1 is a perspective view of a shingle awning, showing my new design.

Figure 2 is a top plan view of the awning.

Figure 3 is a side view of the awning.

Figure 4 is a perspective view of one of the shingles, showing the grooved surface thereof.

I claim:

The ornamental design for a shingle awning or the like, substantially as shown.

LOUIS ARABIT.
